UNITED STATES PATENT OFFICE.

JOHN B. WATLING, OF CHICAGO, ILLINOIS.

DESIGN FOR A MIRROR-FRONT FOR SCALE-CABINETS.

52,715.

Specification for Design.

Patented Nov. 19, 1918.

Application filed May 19, 1917. Serial No. 169,800. Term of patent 14 years.

To all whom it may concern:

Be it known that I, JOHN B. WATLING, a citizen of the United States, and a resident of Chicago, county of Cook, and State of Illinois, have invented a new, original, and ornamental Design for Mirror-Fronts for Scale-Cabinets, of which the following is a specification, reference being had to the accompanying drawing, forming part hereof.

In the drawings, Figure 1 is a perspective view of a mirror front for scale cabinets showing my new design. Fig. 2 is a partial vertical section on an enlarged scale taken on line 2—2 of Fig. 1.

The improved design comprises a mirror A provided with a frame B and having a segmental transparent portion *a* in front of a dial C which is offset behind the mirror.

I claim:—

The ornamental design for a mirror front for scale cabinets substantially as shown.

JOHN B. WATLING.
